United States Patent Office

Des. 208,952
Patented Oct. 17, 1967

208,952

JUG

James A. Shepler, Toledo, Ohio, assignor to Owens-Illinois, Inc., Toledo Ohio, a corporation of Ohio

Filed Oct. 3, 1966, Ser. No. 4,147

Term of patent 14 years

(Cl. D58—5)

FIG. 3

FIG. 1

FIG. 2

The back not shown is a mirror image of the front.

The characteristic features of this design reside in the configurations shown in full lines on the drawing.

I claim:

The ornamental design for a jug, substantially as shown and described.
